UNITED STATES PATENT OFFICE.

JAMES F. ROWLEY, OF CHICAGO, ILLINOIS.

ARTIFICIAL LEG.

1,216,367.

Specification of Letters Patent. Patented Feb. 20, 1917.

Application filed July 16, 1915. Serial No. 40,215.

To all whom it may concern:

Be it known that I, JAMES F. ROWLEY, a citizen of the United States, residing at Chicago, in the county of Cook and State of Illinois, have invented certain new and useful Improvements in Artificial Legs, of which the following is a description.

My invention belongs to that general class of devices known as artificial limbs, and relates particularly to that class of artificial legs known as preparatory or temporary legs. The purpose of using preparatory or temporary legs being well known to those skilled in the art, I have not considered it necessary to set forth in detail the facts relating thereto. My invention has among its objects the production of an improved temporary leg of the kind described that is simple, convenient, comfortable, durable, efficient and satisfactory, and inexpensive to manufacture. It particularly has among its objects the production of an improved leg in which the knee may be flexed in a natural manner, but which, upon rising, will be automatically locked in a simple manner against flexing while walking. It also has among its objects the production of a device in which the socket is free from the framework of the leg, and supported in an exceedingly simple and satisfactory manner so that its adjustment is an easy matter. The construction in its essential parts is adapted for amputation below or above the knee. The drawings show legs for amputations below and above the knee.

To this end my invention consists in the novel construction, arrangement and combination of parts herein shown and described, and more particularly pointed out in the claims.

In the drawings, wherein like reference characters indicate like or corresponding parts,

Figure 1 is a front elevation of my preferred form of leg, the outline of the wearer being shown in dotted lines;

Fig. 2 is an enlarged view of the leg similar to the form shown in Fig. 1;

Fig. 3 is a view in elevation of a form to be used when the amputation is above the knee;

Fig. 4 is a side elevation of the leg shown

in Fig. 1, the same being shown flexed at the knee in the dotted lines;

Fig. 5 is a sectional view substantially on line 4, 4 of Fig. 4;

Fig. 6 is a sectional view substantially on line 5, 5 of Fig. 4, and

Fig. 7 is a sectional view taken substantially on line 6, 6 of Fig. 4.

The socket or corset is preferably made of soft yielding material, such as leather, or its equivalent, and is arranged to be secured together by the lacing 2, extending through the openings 3, so that the same may be laced closer to reduce the diameter, or let out again, should it be necessary. The same is also provided with an additional row of eyelets or openings 4 for lacing, so that the first row may be cut off and the second ones used in the lacing if found necessary. The socket 1 is preferably stiffened and reinforced by one or more strips 5 of metal, or the equivalent, suitably secured thereto, and is formed with the usual apron at the lacing so as to prevent the flesh of the wearer from protruding at the laces. The socket 1 is formed or provided with a strip 6, which may be secured to a belt 7, arranged around the waist of the wearer, as shown in Fig. 1.

The leg proper consists of what might be termed a foot or base 9, which is preferably formed with a pad 10 at the bottom, and with frame members 11, arranged one on each side of the foot 9. In the frame for a leg, in an amputation below the knee, the bars or frame parts 11 are connected to a curved frame part 14, preferably arranged at the back, and this is braced by the frame part 12, secured to the foot, and to part 14. I also provide straps 15—16, and a suitable buckle, or their equivalents for the purpose, so that the frame may be made to normally fit the socket.

Pivotal secured to the side frame 11 are frame parts 17. The part 17 in the construction shown was secured to the side frame 11 by rivets 18, or the equivalent for the purpose, the ends of members 11 projecting above the rivet, as most clearly shown in Figs. 3 and 5. The end of each is also slightly rounded or beveled at the sides and front face. Arranged on the frame part 17 are locking members 24, the operation of

the same being hereafter described. Where I refer to the patient's leg having a portion removed, I shall designate the remaining portion of the leg as the stump or stump legs, in order to avoid confusing the preparatory leg parts with the natural leg. I have shown the side frame 17, provided with a socket or corset 19, of leather, or equivalent material, arranged to be secured together by a lacing 20, these being arranged to be fitted to the stump leg above the knee where the amputation is below the knee.

10 The socket 1 is provided with one or more fastening members 21, arranged to engage with the frame part 14 when the leg is in use, so as to support the same above the foot. The socket 1 is also secured to the frame part 12 by a lacing 22, or equivalent means.

15 The lacing 22 permits the socket 1 to be removed with the leg without withdrawing the leg from the socket. While any equivalent may be employed for the lacing, or the socket may be permanently secured to the framework of the leg by riveting or other-

20 wise, in most cases I prefer the detachable construction, as the socket may be withdrawn with the legs, thereby protecting the same when the preparatory leg is not in use.

25 In use, assuming that the same is provided with a socket 1, arranged on the stump leg, and which is inserted in the preparatory leg substantially as shown in Fig. 1, and secured thereto by the lacing 22. The leg is supported by the supporter 6 in the same

30 support, of course, derived from the upper socket 19, lacing around the stump leg of the wearer. Ordinarily the wearer starts with his crutches and preparatory leg, later abandoning the crutches for a cane, and as

35 he continues to make progress, finally leaves the cane and walks on the preparatory leg without it. If he desires to sit down, he raises the locking members, as shown in the dotted lines in Fig. 5, permitting the leg to

40 be flexed as indicated in Fig. 4. This does away with the unsightly peg sticking out in front of the individual when sitting,—a source of annoyance to others, and of humiliation to the wearer. Upon rising, the locking members 24, by reason of gravity, drop down, as indicated in Figs. 1, 3 and 5, locking the leg against flexing. This is done automatically, and owing to the beveled end of the frame parts 11, as previously referred to, the locking members do not catch, but drop to full or locking position.

45 The construction shown in Fig. 3 is adapted for use where the amputation is above the knee. Referring to the figure, 27 represents the side bars (similar to 11) which are secured to the leg part 26. Pivots secured to 50 27 are the side parts 28, 29 being the locking members similar to the locking members 24. The upper frame consists of the side bars 28 and the bracing members 30, 31 and

55 32 which carry a socket 33 similar to the socket described in the previous construction. The frame is provided with straps 34 and 35, and the detachable socket or corset 1, previously described, is made to fit the upper leg 70 and made secure to the frame part 32 and supported from frame part 30. This leg is used similar to the other one, the only difference being the slight changes necessary to 75 secure the socket 1 in place and the lower support, it being unnecessary to provide a framework for the lower leg as the peg leg part 26 serves the purpose.

80 He will, moreover, have saved the time and expense of a second fitting, and the trouble trying to keep a shrinking stump leg comfortable in a permanent socket. The preparatory leg has all of the essential elements of the artificial limb with the exception of the foot. Many other objects and 85 advantages of the construction herein disclosed will appear to those skilled in the art to which the invention belongs.

Having thus described my invention, it is obvious that various immaterial modifications may be made in the same without departing from the spirit of my invention; hence I do not wish to be understood as 90 limiting myself to the exact form, construction, arrangement and combination of parts 95 herein shown and described, or uses mentioned.

What I claim as new and desire to secure by Letters Patent is:—

1. In a preparatory leg of the kind described and in combination, an adjustable socket member, a supporting frame therefor comprising a foot part provided with a pair of frame members arranged one on each side thereof and connected at the back, said 100 socket member detachably carried by said connection, a bar for each frame member pivotally secured thereto, a socket permanently carried by said bars and means for locking said parts against pivotal movement. 110

2. In a preparatory leg of the kind described and in combination, an adjustable socket member, a supporting frame therefor comprising a foot part provided with a pair of frame members arranged one on each side 115 thereof, and a section frame member pivotally secured to each frame member, a bar connecting one part of said frame bars adjacent their upper ends and outwardly curved toward the rear, a second socket member permanently secured to and carried by said frame bars, means for locking said parts against pivotal movement, and means for detachably securing and supporting said first socket member in place with 120 the curved bar. 125

3. In a preparatory leg of the kind described and in combination, a socket member, a leg for carrying said socket member, comprising a base, a pair of frame members 130

extending upwardly therefrom on the sides, a rearwardly curved brace member secured to and connecting said frame members near the upper ends thereof, a connecting strap 5 extending between said frame members at the front, said socket members provided with hooks arranged to detachably engage said curved brace member on the top edge thereof, and with means for detachably anchoring the lower end, a brace extending from 10 said curved member to the base, and a frame bar pivotally secured to the upper end of each frame member, and means for locking the frame bars against movement as desired, 15 and a socket member secured to and carried by said frame members at the top of the leg.

4. In an artificial leg, the combination of upper and lower parts, said parts provided 20 with extending frame members on each side thereof, secured together to form a knee joint, means for locking the leg against flexing, a rearwardly curved bar connecting said frame members, an adjustable socket member 25 arranged to be secured on the leg stump,

means supporting the socket member within said leg, and means for detachably securing the lower end in place.

5. In an artificial leg of the kind described and in combination, a frame comprising a foot part having an upwardly extending frame part on each side, a bar connecting said frame parts and rearwardly outwardly curved, bracing means for said curved bar at the back intermediate its ends, 30 a strap extending between said frame parts at the front of the leg, a socket permanently carried by the frame at the upper ends of said parts, a second socket provided with lacing means at the front, and with 35 hooks at the rear arranged to detachably engage the upper edge of said curved bar on opposite sides of said brace.

In testimony whereof, I have hereunto signed my name in the presence of two subscribing witnesses.

JAMES F. ROWLEY.
